[57] CLAIM

The ornamental design for an engine accessory mounting bracket, as shown and described.

DESCRIPTION

FIG. 1 is a front perspective view of an engine accessory mounting bracket showing my new design;
FIG. 2 is a partial side elevational view, the right side, as viewed from FIG. 1, being omitted for ease of illustration;

FIG. 3 is a partial side elevational view of the side opposite that shown in FIG. 2, the right side omitted for ease of illustration;

FIG. 4 is a top plan view;

FIG. 5 is a front elevational view;

FIG. 6 is a bottom plan view; and,

FIG. 7 is a rear elevational view.

The broken line showing of an engine accessory in FIGS. 2 and 3 are for illustrative purposes only and forms no part of the claimed design.

FIG.—7
